NARROW FABRIC PACKAGE

Frederic W. Chamberlain, Three Oaks, Mich., assignor to The Warren Featherbone Co., Three Oaks, Mich., a corporation of Michigan

Application April 4, 1931. Serial No. 527,686

8 Claims. (Cl. 206—47)

This invention relates to improvements in narrow fabric packages, and more particularly to the packaging of narrow fabrics such as ribbons, braids and tapes of various kinds, in a convenient form for retailing, and particularly as an item obtainable at a notion counter.

The packaging of narrow fabrics, as for instance by wrapping a certain number of yards on a card, spool or reel, is a well known method of merchandising these products, but with the perfecting of fast color dyes, the use of colors in narrow fabrics for the trimming of dresses, aprons and other wash garments has become the vogue. For example, the so-called bias fold tape now used extensively for edge binding and trimming for both dressmaking and other household arts, can be obtained in a large variety of shades and with the certainty that the colors will be sun-fast and wash-fast. Such trimming materials, however, require thread for sewing or stitching, and heretofore the difficulty has been, first, to match the thread to the tape, and second, having matched the thread, to be assured that it will be as color-fast as the tape. The obvious solution of the problem is to include the required quantity of thread with each package of tape for sewing or stitching, and in this manner the correct matching and fast coloring of tape and thread is assured, if not guaranteed by the manufacturer.

It remains only to devise a practical unit or combination package which will meet the requirements of both producer and consumer, and to fulfill this is the object of the present invention hereinafter disclosed and illustrated in the accompanying drawing, in which

Figure 1 is a perspective view of the complete package.

Figure 2 is a perspective view of the card and tubular cores separated and with the tape and thread removed, and

Figure 3 is a view in side elevation of the filled card and cores assembled in package form.

In making up the present package, a rectangular card 1 has been adopted as the foundation of the package, any ordinary cardboard being used and cut to the required size and shape. As herein shown, the card 1 is elongated, and a given yardage of tape 2 is wound lengthwise thereon. At the ends of the card rectangular notches 1^a, 1^b are cut, being carried well across the ends and considerably deeper than required to accommodate the amount of tape to be wound onto the card. Thus, for example, a card 5 inches long and 2 inches wide, the end notches would be, say,

1½ inches long and ½ inch in depth. The tape neatly wound onto the card thus occupies the space on the card defined by the ends of the notches, but the thickness of the tape is considerably less than the depth of the notches, so that only a small portion thereof is filled, the remaining portions of the notches at each end of the card being adapted to be occupied by cylindric shaped spools 3 of thread matching the color of the tape 2. These spools consist of paper tubes or cores 4 on which is wound the length of thread 5 required for sewing the tape. The thread is wound flat from end to end, but not the full length of the tube, so that short projecting end portions 4^a, 4^b are left exposed.

Now, the length of the tubes 4 is somewhat in excess of the length of the notches, this excess being about equal to the length of the projecting ends 4^a of the tubes, which are notched or slotted diametrically as at 4^b, 4^b, the width and depth of the notches being such that a spool may be fitted lengthwise into each of the notches at the ends of the card by registering the slotted ends of the tubes with the end edges of the notches and forcing them inwardly. Moreover, the outside diameter of the wound tubes is substantially equal to the depth of the notches after the tape has been wound on the card, so that end edges of the card and spools are flush with each other, when the package is assembled as shown in Figure 3. And finally, the spools have about the same diameter as the thickness of the wound tape, so that the package has practically no greater bulk than an unnotched card of the same size carrying only the tape.

The spools 3 thus incorporated in the package can be readily removed from the card by drawing them endwise from the notches, although there is a sufficient binding or frictional engagement between the slotted ends of the tubes and the card to hold them securely in place. In completing the package, however, a paper band 6 is preferably wrapped transversely around the central portion of the filled card, and then the whole enclosed within a wrapper or envelope 7 of transparent material such as cellophane, so that until the package is broken for use, the contents remain assembled in a compact combination of tape and thread.

Other methods of combining or packaging a quantity of thread with narrow fabrics to form a unit package may have been devised, but certain advantageous features of the present arrangement are to be noted.

In the first place, the thread is wound on a

separate core and the core detachable from the card, so that the carded tape and spooled thread are separate units which remain intact whether combined or separated. This manifestly permits either the tape or thread to be used without disturbing the other, which would not be the case, for instance, if the thread were wound upon the card with or over the tape or upon some member attached to the card in such a way that the tape could not be unwound until the thread had been unwound, or vice versa.

Another advantage of the present package is the provision of two spools of thread. Bearing in mind that the tape would ordinarily be stitched on a sewing machine, one spool may be thus placed directly on the spindle of the machine for threading the needle, while the other is used for filling the bobbin. To this end, therefore, the cores are not only tubular but are dimensioned so that the spools can be mounted on a sewing machine in the same way as ordinary spooled thread.

Having set forth a preferred embodiment of my invention, I claim:

1. A package of narrow fabric comprising a card on which said fabric is wound, and having a notch in one edge thereof, a spool of thread adapted to occupy the space provided by said notch, and having a tubular core detachably connected at its ends with the adjacent edges of the card at the ends of the notch.

2. A package of narrow fabric comprising a card on which said fabric is wound, and having a notch in one edge thereof, a spool of thread adapted to fit within the space provided by said notch and provided with slotted ends adapted to engage the end edges of said notch.

3. A package of narrow fabric comprising a card on which the fabric is wound, and having an elongated rectangular recess in one edge thereof and a spool consisting of a cylindric core having a quantity of thread wound thereon and slotted across its ends, said spool being adapted to be removably inserted in said recess with the slotted ends of said core engaged by the edges of said card at the ends of said recess.

4. A package of narrow fabric comprising a

card on which the fabric is wound, and having an elongated rectangular recess in one edge thereof, a spool consisting of a tubular core having thread wound flatly thereon and pairs of endwise opening slots cut in the ends thereof, said spools being removably retained in said recess with its slotted ends engaged by the end edges of said recess.

5. A package of narrow fabric comprising a card on which the fabric is wound and having an elongated rectangular recess in one edge thereof, a spool consisting of a cylindric core having thread wound flatly thereon with portions projecting at each end, and diametrically arranged slots cut in the ends thereof, said spools being removably retained in said recess with its slotted ends engaged by the end edges of said recess.

6. A package of narrow fabric comprising a card having oppositely disposed recesses formed in parallel edges, and having a quantity of the narrow fabric wound thereon to occupy a portion of the depth of the recesses, spools of thread adapted to fit within said recesses and each including a core substantially longer than said notches and having slots extending diametrically of its ends and adapted to have interlocking sliding engagement with the edges of said card at the ends of its recess.

7. A package of narrow fabric comprising a card having a rectangular recess formed at one end thereof and a quantity of narrow fabric wound thereon to occupy a portion of the depth of said recess, a spool of thread including a core adapted to fit within the space of said recess beyond the fabric and having its end slotted to engage the corresponding edge of the recess.

8. A package of narrow fabric comprising a card having rectangular recesses formed at opposite ends and a quantity of the narrow fabric wound thereon to occupy a portion of the depth of the recesses, tubular paper cores adapted to fit within said recesses beyond the fabric and having thread wound flatwise thereon, with slotted end portions adapted to engage the ends of said recesses.

FREDERIC W. CHAMBERLAIN.
